(57) **CLAIM**

An ornamental design for the column mountable player tracking display, as shown and described.

DESCRIPTION

FIG. 1 is an isometric view of my column mountable player tracking display showing my new design. A pair of speaker grills, player-card slot, and possible environment are shown in dashed lines, and are not part of the claimed design; FIG. 2 is a front elevational view of the design of FIG. 1; FIG. 3 is a top plan view of the design of FIG. 1; FIG. 4 is a left side elevational view of the design of FIG. 1; FIG. 5 is a right side elevational view of the design of FIG. 1; FIG. 6 is a rear elevational view of the design of FIG. 1; and, FIG. 7 is a bottom plan view of the design of FIG. 1.
